UNITED STATES PATENT OFFICE.

BYERS W. KADEL, OF BALTIMORE, MARYLAND.

CAR-DOOR-LOCKING MECHANISM.

Application filed June 2, 1927. Serial No. 196,063.

My invention relates to car door locking mechanism, and more particularly to locks for retaining in closed position hinged doors adapted to swing to open position under the influence of gravity to permit the lading of the car to be discharged. The principal object of the invention is to provide strong and efficient means for forcing a movable door locking member to and from locked position.

10 A primary feature of the invention consists in providing a door locking mechanism having a fixed member and a movable member with means for forcing the door to closed position upon movement of the last named member to locked position and in combining therewith means affording a plurality of fulcrum points for a removable lever adapted to force the pivoted member to and from locked position.

15 Another feature of the invention consists in providing a fixed locking member on the car body and a pivoted locking member on the door, the members being arranged for wedging engagement to force the door to closed position, and in associating therewith means carried by the car body having spaced portions affording fulcrum points for a removable lever passing therebetween, whereby upon engagement of said lever with one 20 of said fulcrum points the pivoted member may be forced to locked position and upon engagement of said lever with the other of said fulcrum points the pivoted member may be forced to unlocked position.

25 Another and more specific feature of the invention consists in affording, in combination with the gravity actuated door of a railway car, door supporting mechanism involving a member fixed on the car body and a member pivoted on the door, said members having wedging cooperation for forcing the door to closed position, and in combining herewith a loop member rigid with the fixed member having upper and lower portions 30 forming respectively fulcrum points for a removable lever adapted to cooperate with the pivoted member for forcing the latter into and out of engagement with the fixed member.

35 Other features of the invention residing in particular details of construction and combination of parts, will hereinafter appear and be pointed out in the claims.

In the drawings illustrating a preferred embodiment of the invention.—

Figure 1 is a fragmentary side elevational view of a portion of one of the hoppers of a railway car of a well known type showing mechanism involving the invention applied thereto.

Figure 2 is a fragmentary end elevational view of the construction shown in Fig. 1.

Figure 3 is a side elevational view similar to Fig. 1, showing the door in a position of partial closure.

As the door locking mechanism embodying the invention is shown as applied to a railway car of a type in common use, only a portion of one of the hoppers of the car has been illustrated. The hopper portion of the car may be constructed in the usual manner with hopper side sheets 1 and a slope sheet 2. The outer or free ends of these plates which are reinforced by the member 3 define the opening through which lading is discharged from the hopper. This discharge opening is normally closed by the swinging door 4 which may be hinged to the car body in any desired or usual manner (not shown) so as to swing to open position under the influence of gravity. The door 4 may advantageously be constructed of sheet metal and is preferably provided with marginal flanges 5 serving to stiffen it.

While there is illustrated a single hopper and a portion of the coating door it will be understood that the construction is duplicated on the opposite side of the car center sill and that the door shown is but one of a pair of doors rigidly connected by a spreader 90 or stiffening member 6 so as to cause said doors to operate as a single unit. In the present instance this spreader member is of channel section having lateral flanges 7 secured to the outer face of the door by rivets 8.

Rigidly attached to the outer side of the side sheet 1, preferably by means of rivets 9, is a hook member 10 whose outer end projects beyond the plane of the hopper discharge opening. The hook is fashioned with a beveled or inclined portion 11 terminating in a shoulder or ledge 12.

Pivottally mounted on the door by means of a pivot post or rivet 13 in overlapping 105 relation to the outer face of the connecting

web 14 of the spreader 6, is a latch member 15 movable into engagement with the ledge 12 of the hook for supporting the door in closed position. A housing or cover plate 16, secured to the door by rivets 17, overlies the pivot end of the latch for preventing the latter from moving away from the door when it contacts with the approach plane 18 of the hook during closing movement of the door. 10 The web portions of the housing 16 and spreader 6 are effectively secured together by the pivot rivet 13.

As is well known, it is often very difficult to effect a complete closure of the swinging doors of hopper cars. This is due to the fact that the doors become warped or distorted because of the service to which they are subjected, and moreover, small pieces of lading sometimes lodge in positions making complete closure of the doors a matter of considerable difficulty. It is, however, usually possible in cars of the character wherein the doors on opposite sides of the center sills are connected to operate as a unit, to effect complete closure of one side of the door and a partial closure of the opposite side. In the present instance complete closure of the partially closed side of the door is effected by rotating the latch 15 into engagement with the beveled or inclined surface 11 of the hook. It can readily be seen that as the latch rides downwardly on this surface the wedging action of these two members effectively forces the door to its fully closed position.

As considerable force is required to cause the latch to execute a locking rotation for forcing the door to fully closed position and as some force is also required to rotate the latch in the opposite direction to permit the discharge of lading, means is provided on the car body for cooperating with a removable lever 19 to effect a rotation of the latch in the desired direction. This means which is preferably formed rigid with the hook 10 consists of a loop 20 having spaced upper and lower portions or arms 21 and 22, respectively, forming fulcrum points for the removable lever. When it is desired to move the latch to locked position and thereby force the door to fully closed position the lever is inserted through the loop into engagement with the upper edge of the latch, as shown in Figure 3. Upon applying an upward force to the opposite end of the lever the upper portion 21 of the loop functions as a fulcrum on which the lever rotates. For moving the latch to unlocked position, the lever is brought into engagement with the lower edge of the latch, as shown in Figure 1, and the lower portion 22 of the loop then functions as the fulcrum point around which the lever rotates upon application of a downwardly directed force to the opposite end of the latter.

A cam 23 is provided for preventing accidental displacement of the latch from door supporting position. The cam is pivotally connected by a pin 24 to the strap or housing 25 which is secured to the outer face 70 of the door, preferably by rivets 26. In order that the cam 24 may not interfere with the upward movement of the latch as it rides on the approach plane of the hook during closing movement of the door, a removable pin 27 is provided for maintaining the cam in a raised position, as shown in dotted lines in Figure 2. The pin is preferably connected to a chain 28 which may be secured to some adjacent portion of the door such as the strap 25. It will be appreciated that the pin may also function to prevent accidental disengagement of the cam from the latch.

I claim:

1. A railway car having a lading discharge opening, a door for said opening movable to open position under the influence of gravity, means for supporting the door in closed position involving a shouldered member and a beam member, one of said members being fixed with respect to the part upon which it is mounted and the other being pivoted with respect to the part upon which it is mounted, and one of said members being provided with an inclined portion cooperable with the other of said members to force the door to closed position upon a locking rotation of the pivoted member, and means carried by the car body forming a plurality of fulcrum points respectively adapted to cooperate with a removable lever for forcing the pivoted member into and out of door supporting position.

2. A railway car having a lading discharge opening, a door for closing said opening movable to open position under the influence of gravity, mechanism for supporting the door in closed position involving a shouldered member carried by the car body and a beam member carried by the door one of said members being fixed with respect to the part upon which it is mounted and the other being movable with respect to the part upon which it is mounted, one of said members having an inclined portion adapted for engagement with the other of said members for wedging the door to closed position, and means carried by the car body affording a plurality of fulcrum points for a removable lever adapted to force the movable member to and from locked position.

3. A railway car having a lading discharge opening, a door for closing said opening movable to open position under the influence of gravity, a hook member fixedly mounted on the car body, a latch member pivotally mounted on the door and cooperable with the hook for supporting the door

in closed position, one of said members being fashioned with an inclined portion engageable with the other of said members for wedging the door to closed position, and 5 means rigid with one of said members affording a plurality of seats for a removable lever whereby upon engagement of said lever with one of said seats the latch may be forced to locked position and upon engagement of said lever with the other of 10 said seats the latch may be forced to unlocked position.

4. A railway car having a lading discharge opening, a door for closing said opening movable to open position under the influence of gravity, means for supporting said door in closed position involving a fixed shouldered member carried by the car body and a pivoted latch member carried by the 20 door, an inclined portion on said fixed member adapted to cooperate with said pivoted member for forcing the door to closed position, and means carried by the car body forming a plurality of fulcrum points for 25 a removable lever adapted to force said pivoted member to and from locked position.

5. A railway car having a lading discharge opening, a door for closing said opening movable to open position under the influence of gravity, means for supporting said door in closed position involving a fixed member and a pivoted member, one of said members being carried by the car body and the other by the door, one of said members 30 having an inclined portion cooperable with the other of said members for wedging the door to closed position, and means carried by the car body having spaced portions affording fulcrum points for a removable 35 lever passing therebetween, whereby upon engagement of said lever with one of said fulcrum points the pivoted member may be forced to locked position and upon engagement of said lever with the other of said fulcrum points the pivoted member may be 40 forced to unlocked position.

6. A railway car having a lading discharge opening, a door for closing said opening movable to open position under the influence of gravity, means for maintaining the door in closed position involving a fixed member and a pivoted member, one of said members being carried by the car body and the other by the door, said members having 45 wedging engagement for forcing the door to closed position, and means carried by the car body having upper and lower portions forming fulcrum points for a removable lever so that upon engagement of the lever with the upper portion the latch may be forced to locked position and upon engagement of the lever with the lower portion the latch may be forced to unlocked position.

7. A railway car having a lading discharge opening, a door for closing said open-

ing movable to open position under the influence of gravity, door supporting mechanism involving a member fixed on the car body and a member pivoted on the door, said members having wedging cooperation 70 for forcing the door to closed position, and a loop member rigid with the fixed member having upper and lower portions forming fulcrum points for a removable lever adapted to cooperate with the pivoted member for 75 forcing the latter into and out of engagement with the fixed member.

8. A railway car having a lading discharge opening, a door for closing said opening movable to open position under the influence of gravity, mechanism for supporting the door in closed position involving a fixed member and a movable member, one of said members being carried by the door and the other by the car body, said members having 80 wedging engagement for forcing the door to closed position upon movement of the movable member to door supporting position, and means associated with the mechanism 85 affording a fulcrum for a removable lever whereby the movable member may be forced to said door supporting position.

9. A railway car having a lading discharge opening, a door for closing said opening movable to open position under the influence of gravity, mechanism for supporting the door in closed position involving a shouldered member carried by the car body and a beam member carried by the door, one of said members being fixed with respect to 90 the part upon which it is mounted and the other being pivoted with respect to the part upon which it is mounted, a wedging surface on one of said members for forcing the door to closed position upon movement 95 of the pivoted member to door supporting position, and means associated with the mechanism affording a fulcrum for a removable lever whereby the pivoted member may be forced to said door supporting position. 100

10. A railway car having a lading discharge opening, a door for closing said opening movable to open position under the influence of gravity, means for supporting the door in closed position involving a fixed member carried by the car body and a movable member carried by the door, one of said members being provided with a wedging surface cooperable with the other of said members for forcing the door to closed 115 position upon movement of the movable member to door supporting position, and means carried by the car body affording a fulcrum for a removable lever adapted to force the movable member to said door supporting position. 120

11. A railway car having a lading discharge opening, a door for closing said opening movable to open position under the influence of gravity, a hook fixed on the car 130

body, a latch pivoted on the door cooperable with the hook for supporting the door in closed position, the said hook being provided with an incline engageable with the latch so that upon movement of the latter to door supporting position the door will be forced to closed position, and means project-

ing outwardly from the car body forming a fulcrum for a removable lever adapted to force the pivoted latch to said door supporting position. 10

In testimony whereof I affix my signature.
